UNITED STATES PATENT OFFICE.

JOHAN KLOBUCHAR, OF STEUBEN, MICHIGAN.

RAIL-JOINT.

1,232,332.

Specification of Letters Patent.

Patented July 3, 1917.

Application filed March 23, 1917. Serial No. 156,877.

To all whom it may concern:

Be it known that I, JOHAN KLOBUCHAR, a subject of the King of Hungary, residing at Steuben, in the county of Schoolcraft and 5 State of Michigan, have invented certain new and useful Improvements in Rail-Joints, of which the following is a specification.

This invention relates to certain new and 10 useful improvements in rail joints.

The primary object of the invention is the provision of a ready means for retaining railway rails operatively positioned in longitudinal alinement without the employment 15 of screws, bolts or the usual securing members.

A further object of the device is the provision of a rail joint structure which possesses great strength and is readily employed 20 in connection with the usual form of railway rails by providing suitably positioned perforations through the web and the base flanges thereof, the device being retained upon the ties in any desired manner.

25 In the drawing forming a part of this application and in which like designating characters refer to corresponding parts throughout the several views:—

Figure 1 is a side elevation of the adjacent 30 end portions of railway rails operatively connected together by the present device.

Fig. 2 is a top plan view thereof with an end portion of the same partially broken away and illustrated in horizontal section.

35 Figs. 3 and 4 are vertical transverse sectional views taken upon lines III—III and IV—IV of Fig. 1.

Fig. 5 is a perspective view of an end portion of a locking fish plate employed 40 with the device, and,

Fig. 6 is a perspective view of one of the locking pins employed.

The present form of connector is herein 45 illustrated in connection with railway rails 10 and 11 positioned in alinement with each other with the end faces thereof abutting one another.

The connector consists of a two-part inclosing frame for the adjacent end portions 50 of the rails 10 and 11 comprising the main section 12 having a base 13 upon which the base flanges 14 of the rails are adapted to seat with an angular side 15 of the section 12 engaging over one side of the base 55 flange in flat engagement with one side of

the webs 16 of the rails and beneath and in contact with the rail treads 17.

A fish plate section 18 completes the inclosing frame for the rails, said fish plate having a side portion 19 for engaging the rail web 16 and an angularly projecting flange 20 for overlying the adjacent base flanges of the rails. An upwardly-extending marginal flange 21 is provided at the free edge of the frame base 13 spaced from the adjacent edge of the base 14 of the rail when seated therein, a depending substantially triangular extension 22 being arranged upon the flange 20 for reception between the frame flange 21 and the base flange of 70 the inclosed rails. The flange 21 has a V-shaped inner edge 23 adapted for reception within a correspondingly-shaped groove 24 at the outer edge of the fish plate flange 20.

An upwardly projecting lug 25 is carried upon the base 13 for each of the rails 10 and 11, the said rails each having a perforation 26 through the base flange thereof for seating over the said lugs, the rails being beveled at the perforations as shown 80 in Fig. 4 to permit the reception of the lugs 25. It will be understood that the frame 12 may be positioned upon the roadbed or upon ties as desired and that the ends of the rails 10 and 11 may be readily positioned in place upon the frame base 13 with the perforations 26 overlying the lugs 25, it being understood that the said perforations and lugs are accurately positioned for bringing the end faces of the rails substantially into engagement with each other when so arranged. A tapered opening 26' is provided through the web 16 of each of the rails while a tapered passage 27 is provided in the adjacent portion 15 of the frame 12 95 for alinement therewith when the rails are operatively positioned, tapered locking pins 28 being adapted for insertion through the opening 26' and into the passages 27, with the inner ends of the pins lying substantially 100 flush with the face of the receiving web.

The fish plate 18 is then slidably positioned in place in engaging position upon the rails 10 and 11 opposite the frame portion 15 and overlying the locking pins 28 105 and the lugs 25. The said fish plate being snugly seated in its engaging position as herein illustrated, the rails 10 and 11 are rigidly maintained in their operative positions in longitudinal alinement while the 110

- entire structure may be firmly secured to ties (not shown) by arranging spikes through open notches 29 at the outer edge of the frame 12 as well as through openings 30 at 5 the opposite side of the frame base 13 which openings extend through the flange 21 of the frame and the flange 22 of the fish plate 18 in the form of alining notches 31 and 32 respectively, when the device is assembled. 10 The rails 10 and 11 being securely connected together by the present device, it will be understood that the arrangement of spikes (not shown) through the notches 29 and 15 openings 30 retains the structure upon the road-bed as well as locking the fish plate 18 against removal by being withdrawn from the frame 12.

What I claim as new is:—

1. A rail joint comprising a frame having 20 a mounting base, and an angular rail-engaging side provided with tapered passages therethrough, rail-engaging locking pins removably insertible within the said passages, upstanding rail-positioning lugs carried by 25 the said base, an upwardly-extending marginal flange carried by the said base, having a V-shaped inner edge, and an angular fish plate slidably carried by the frame overlying said pins and having a V-shaped groove

within which the said flanged edge is positioned when the device is operatively assembled. 30

2. A device of the class described comprising in combination with abutting railway rails having passages through the webs thereof and perforations through their base flanges, a frame having a base upon which the said rails are seated and further having an angular side engaging the webs of the rails and provided with openings therethrough in alinement with the said web openings, locking pins arranged through the said openings and passages, positioning lugs upon the said base arranged within the said perforations, an upwardly projecting marginal flange upon the said base having a tapered inward edge, a fish plate adapted for engaging the webs and base flanges of the rails provided with a depending extension slidably arranged within said flange of the base and having a groove in its outer face adapted for the reception of the said edge, the said base with its flange and the flange and extension of the fish plate having openings therethrough adapted for the reception 55 of a positioning spike. 40 45 50 55

In testimony whereof I affix my signature.

JOHAN KLOBUCHAR.
